UNITED STATES PATENT OFFICE.

WELCOME PENSON GAMMONS, JR., AND GEORGE STEPHEN BRACHER, OF NEW YORK, N. Y.

HAT.

SPECIFICATION forming part of Letters Patent No. 591,755, dated October 12, 1897.

Application filed June 24, 1897. Serial No. 642,167. (No model.)

To all whom it may concern:

Be it known that we, WELCOME PENSON GAMMONS, Jr., and GEORGE STEPHEN BRACHER, citizens of the United States, residing at New York, in the county of New York and State of New York, have invented certain new and useful Improvements in Hats; and we do declare the following to be a full, clear, and exact description of the invention, such as will enable others skilled in the art to which it appertains to make and use the same.

Our invention relates to hats; and it will be fully understood from the following description and claim, when taken in conjunction with the annexed drawings, in which—

Figure 1 is a perspective view of a hat with the binding attached thereto according to our invention, and Fig. 2 is a detail transverse section on an enlarged scale.

Referring by numerals to the said drawings, 3 indicates a hat having a stiff, curled, or rolled brim 2.

1 indicates the binding or binding-tape, and 4 indicates the stitches which connect 25 the inner edge of the binding to the inner side of the brim and extend through said brim.

An understanding of the invention may be best imparted by describing the manner in which the binding is applied to the stiff, 30 curled, or rolled brim, and therefore this course will be pursued. We prefer in practice to start the stitching at the back of the hat and stitch entirely around the brim to the point of commencement, the inner edge of 35 the binding resting at the inner side of the brim and the stitches 4 extending through the brim, as shown in Fig. 2. After the piece of binding has been attached along one edge and throughout its length to the inner 40 side of the stiff hat-brim by the stitches 4 its ends are “snapped” or sewed together, as indicated by 5, after which it is turned outwardly over the curled brim, when it will tightly fit and snugly conform to the brim, 45 and, while presenting a smooth and finished appearance, will securely hold the binding on the brim, thus rendering it unnecessary to connect the binding to the outer side of the brim. The tight fit of the binding on the

brim when said binding is applied as just 50 described is due to the fact that the outer side of the brim is larger than the inner side, and consequently when the ends of the binding are snapped or connected together, after the inner edge of said binding is connected 55 to the brim and before it is turned over the same, the free edge of the binding is strained and sprung over the brim under considerable tension, varying according to the thickness 60 of the felt or other material of which the stiff 65 brim is composed. This, as stated, renders the binding very tight upon the brim and makes it conform snugly to the same with the result that a neat and smooth finish is presented, and at the same time the binding is 70 secured of itself upon the brim. Again, when the binding is so placed it covers and protects the connecting-stitches from the action of the elements and thus prevents rotting, fading, or other deterioration of the thread 75 forming such stitches. The covering of the connecting stitches also prevents the thread forming the connecting-stitches from being worn and broken by a brush when the hat is frequently brushed.

Having described our invention, what we claim, and desire to secure by Letters Patent, is—

A hat having a stiff, curled or rolled brim, and a binding-tape having its inner edge connected to the inner side of the brim by stitches extending transversely through the brim, and also having its ends sewed together; the said binding resting under tension over the edge and against the outside of the brim and 85 over the stitches connecting the binding-tape to the brim, whereby the binding-tape is secured of itself to said edge and outside of the brim to cover and protect the connecting-stitches, substantially as specified. 90

In testimony whereof we affix our signatures in presence of two witnesses.

WELCOME PENSON GAMMONS, JR.
GEORGE STEPHEN BRACHER.
